(57) **CLAIM**

The ornamental design for a dual input power supply as
shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a first embodiment of a dual input
power supply showing our new design;

FIG. 2 is a back view of a first embodiment thereof;

FIG. 3 is a left view of a first embodiment thereof;

FIG. 4 is a right view of a first embodiment thereof;

FIG. 5 is a top view of a first embodiment thereof;

FIG. 6 is a bottom view of a first embodiment thereof;

FIG. 7 is a front and left side perspective view of a first
embodiment thereof;

FIG. 8 is a back and right side perspective view of a first
embodiment thereof;

FIG. 9 is an enlarged view taken from line 9 in FIG. 7;

FIG. 10 is an enlarged view taken from line 10 in FIG. 8;

FIG. 11 is a front view of a second embodiment thereof;

FIG. 12 is a back view of a second embodiment thereof;

FIG. 13 is a left view of a second embodiment thereof;

FIG. 14 is a right view of a second embodiment thereof;

(Continued)

FIG. 15 is a top view of a second embodiment thereof;
 FIG. 16 is a bottom view of a second embodiment thereof;
 FIG. 17 is a front and left side perspective view of a second embodiment thereof;
 FIG. 18 is a back and right side perspective view of a second embodiment thereof;
 FIG. 19 is a front view of a third embodiment thereof;
 FIG. 20 is a back view of a third embodiment thereof;
 FIG. 21 is a left view of a third embodiment thereof;
 FIG. 22 is a right view of a third embodiment thereof;
 FIG. 23 is a top view of a third embodiment thereof;
 FIG. 24 is a bottom view of a third embodiment thereof;
 FIG. 25 is a front and left side perspective view of a third embodiment thereof;
 FIG. 26 is a back and right side perspective view of a third embodiment thereof;
 FIG. 27 is a front view of a fourth embodiment thereof;
 FIG. 28 is a back view of a fourth embodiment thereof;
 FIG. 29 is a left view of a fourth embodiment thereof;
 FIG. 30 is a right view of a fourth embodiment thereof;
 FIG. 31 is a top view of a fourth embodiment thereof;
 FIG. 32 is a bottom view of a fourth embodiment thereof;
 FIG. 33 is a front and left side perspective view of a fourth embodiment thereof; and,
 FIG. 34 is a back and right side perspective view of a fourth embodiment thereof.

The evenly spaced broken lines shown in the figures contain lightly shaded areas that depict the portions of the dual input power supply that form no part of the claimed design. The dash-dot broken lines that encircle portions of FIGS. 7 and 8 and that border the FIGS. 9 and 10 indicate outer limits of enlarged areas of the figures and form no part of the claimed design. The design does not claim protection for a specific coloring.
